SIGN BOARD

Robert B. Gibson, Denver, Colo.

Application June 22, 1955, Serial No. 36,631

Term of patent 3½ years

(Cl. D1—12)

Figure 1 is a perspective view of a sign board, showing my new design;

Figure 2 is a top plan view thereof; and

Figure 3 is a side elevational view of the same.

The dominant features of my design reside in the portions shown in full lines.

I claim:

The ornamental design for a sign board, as shown and described.
